US00D870369S

(12) **United States Design Patent** (10) **Patent No.:** **US D870,369 S**
(45) **Date of Patent:** **** Dec. 17, 2019**

(54) **VAPORIZATION DEVICE**

(71) Applicant: **GLAS, Inc.**, Los Angeles, CA (US)

(72) Inventors: **Sean Greenbaum**, Los Angeles, CA (US); **Frank Nuovo**, Los Angeles, CA (US)

(73) Assignee: **GLAS, INC.**, Los Angeles, CA (US)

(**) Term: **15 Years**

(21) Appl. No.: **29/680,301**

(22) Filed: **Feb. 14, 2019**

(51) LOC (12) Cl. **27-07**

(52) U.S. Cl.

USPC **D27/162**

(58) **Field of Classification Search**

USPC D27/100, 101, 161, 162–194; D23/366; D24/110; D19/101, 106, 115, 165, 195; D14/435.1

CPC A24F 47/00; A24F 47/002; A24F 15/12

(57) **CLAIM**

The ornamental design for “a vaporization device,” as shown and described.

DESCRIPTION

FIG. 1 is a perspective view of a vaporization device, the vaporization device including a body and a cartridge received within the body;

FIG. 2 is a front view of the vaporization device of FIG. 1; FIG. 3 is a rear view of the vaporization device of FIG. 1; FIG. 4 is a right-side view of the vaporization device of FIG. 1;

FIG. 5 is a left-side view of the vaporization device of FIG. 1;

FIG. 6 is a top view of the vaporization device of FIG. 1; and,

FIG. 7 is a bottom view of the vaporization device of FIG. 1.

In the drawings, the broken lines represent unclaimed subject matter and form no part of the claimed design.

1 Claim, 3 Drawing Sheets
